WHEEL CYLINDER FOR HYDRAULIC BRAKES

Sylvan H. Sime, Kiester, Minn.

Application April 28, 1947, Serial No. 744,288

7 Claims. (Cl. 60—54.6)

1

This invention relates to a hydraulically operated system for projecting a projectable element against a cooperating element and particularly to means for maintaining a predetermined relationship between said projectable element in normal position and said cooperating element. This invention has particular application for use on hydraulic braking systems whereby a predetermined clearance between the brake-shoe and drum may be maintained.

The adjustment of brakes for automobiles has long been a problem for automobile owners. It requires periodic attention to keep the brakes in proper adjustment. Due to the wear on the brake-shoe the clearance between the drum and the shoe constantly increases on present brake systems so that the distance that the brake pedal must move is always constantly increased.

It is a general object of my present invention to provide a device to operate in conjunction with a hydraulic system whereby a predetermined clearance may be maintained between a projectable element of said system and an element adapted to cooperate with said projectable element.

More specifically it is an object of my invention to provide a device particularly designed for application to hydraulic braking systems for the modern automobile whereby a predetermined clearance between the brake-shoe in normal position and the brake drum may be maintained without manual adjustment.

These and other objects and advantages of my invention will be more apparent from the following description made in connection with the accompanying drawings wherein like reference characters refer to similar parts throughout the several views, and, in which:

Figure 1 is a central longitudinal vertical sectional view of a hydraulic cylinder embodying my invention;

Figure 2 is a top plan view of the cylinder shown in Figure 1 with a portion of the cylinder casing cut away;

Figure 3 is a transverse vertical sectional view taken substantially on the line 3—3 of Figure 1;

Figure 4 is a longitudinal vertical sectional view through the outer portion of a standard brake-shoe and drum assembly showing said brake-shoe and my wheel cylinder mounted therein in elevation; and

Figure 5 is a central longitudinal vertical sectional view of an alternative form of my invention showing a particular adaptation of said alternative form to a brake-shoe and drum assembly.

As illustrated in Figures 1 through 4 I provide a wheel cylinder designated as an entirety by the letter A. When speaking of the wheel cylinder A I include the entire assembly illustrated in Fig-

2

ures 1 through 3. This wheel cylinder A comprises an elongated casting 10 forming piston cylinders 11 disposed longitudinally in the end portions thereof and extended inwardly a substantial distance. Hydraulic pistons 12 are slidably inserted into piston cylinders 11, the inner peripheries of the piston cylinders 11 sealingly embracing the outer peripheries of pistons 12. Sealer caps 13 are mounted against the inner ends of pistons 12 and have their outer faces tightly engaged thereagainst. The inner faces of sealer caps 13 are recessed to form peripheral flanges 13a providing a relatively wide peripheral surface which sealingly engages the inner periphery of piston cylinder 11.

A central inlet passage 15 is drilled horizontally and transversely into the central body portion of the casting 10 and has its inner end terminating in substantially the center of said casting 10. The outer end of said inlet passage 15 is adapted to be connected to a hydraulic fluid supply line (not shown). A pair of branch inlets 16 are drilled longitudinally through the center of casting 10 and have their inner ends communicating with the end portion of inlet passage 15. Valve cylinders 17 are formed longitudinally in said casting 10 between the inner end of piston cylinders 11 and the outer ends of branch inlets 16. A pair of vertical by-pass passages 18 are drilled vertically and transversely in said casting 10 and intersect valve cylinders 17 a slight distance outwardly from the inner ends thereof. A pair of cap screws 19 are screwed into the outer end portions of by-pass passages 18 leaving only relatively short passages 18. A pair of longitudinal openings 20 connect the inner ends of piston cylinders 11 with the outer ends of by-pass passages 18 and have their inner ends disposed substantially adjacent the inner ends of cap screws 19 forming a smooth passage without recesses in which air might be trapped. A pair of horizontal bleeder holes 21 communicate with the inner ends of piston cylinders 11 to permit any air within the system to escape when the hydraulic system is initially filled with hydraulic fluid. During operation of the brakes these bleeder holes will be plugged as by cap screws (not shown).

Valve pistons 22 having recessed sealer caps 23 engaging the inner ends thereof are inserted into valve cylinders 17 and have their outer ends connected with the inner diminished ends of the conical springs 14. The recessed valve sealer caps 23 on the inner ends of pistons 22 form peripheral sealer flanges 23a and the inner ends of the valve cylinders 17 have peripheral recesses 17a to receive and cooperate with the sealer flanges 23a, to permit the central recessed portions of sealer caps 23 to sealingly engage against

the central annular projections surrounded by recesses 17a.

A pair of projectable rods 24 extend outwardly from the outer ends of hydraulic pistons 12 and have their inner ends engaging a recessed central portion in the outer surface of pistons 12 and have their outer ends connected to the upper portions of brake-shoes 25 and 26 as shown in Figure 4. A brake-shoe retraction spring 27 has its outer ends connected with the upper portions of the brake-shoes 25 and 26 to resiliently urge said brake-shoes into retracted or normal position.

A brake drum 28 is adapted to have its inner periphery receive the outer periphery of brake-shoes 25 and 26 and to completely surround said brake-shoes 25 and 26. The brake drum 28 is fixed to an automobile wheel (not shown) and rotates therewith.

A backing plate 29 is rigidly fixed to a non-rotatable portion of the automobile as by cap-screws through the apertures 29a. The wheel cylinder A is horizontally fixed on the upper portion of said backing plate 29 and has its projectable rods 24 pivotally attached to the upper portion of brake-shoes 25 and 26. The lower portion of brake-shoes 25 and 26 are pivotally connected with the outer ends of links 30 the inner ends of links 30 being mounted on a pin 31 which is rigidly connected with the lower portion of said backing plate.

Operation

In the operation of a standard wheel cylinder as is now in use the fluid under pressure from the master cylinder (not shown) enters as through the inlet 15 to flow directly into the piston cylinders 11 to operate the pistons 12 and move the projectable rods 24 and the brake-shoes 25 and 26 outwardly to engage against the inner peripheral surface of the brake drum 28. When the automobile wheel is rotating in the direction indicated by the arrow in Figure 4 brake-shoe 25 will be the primary shoe and brake-shoe 26 becomes the secondary shoe. Due to the frictional force exerted between the shoe 25 and the drum 28 the rotation of the drum will tend to "drag" the upper portion of the brake-shoe 25 more tightly against the drum 28 while the same rotation will tend to push the upper portion of the secondary shoe 26 away from the drum 28. The links 30 as shown in Figure 4 serve to equalize the pressure between the primary and the secondary shoes 25 and 26 in that the lower end of secondary shoe 26 is mounted in floating relationship in relation to the drum 28 and thus the rotation of the drum 28 will tend to "drag" the lower end of secondary shoe 26 against it increasing the pressure thereon and more or less equally distributing the force exerted between the two shoes 25 and 26. This linkage arrangement or some other means for equalizing the pressure exerted by the two shoes is in use on most of the modern cars today and does not constitute a pair of my invention.

The mechanism of my wheel cylinder A is shown in extreme brake-operating position in Figures 1 and 2. My hydraulic system is "bled" in the same manner as conventional hydraulic systems. The bleeder holes 21 are opened and hydraulic fluid is pumping into the wheel cylinder from the master cylinder (not shown) by pumping the brake pedal (not shown) until all the air in the system has been displaced by fluid. The bleeder holes 21 are then plugged.

To initially adjust the brakes to a predetermined

clearance between the shoes 25 and 26 and the drum 28, the brake pedal (not shown) is pushed down to operate the master cylinder (not shown). Hydraulic fluid is thus forced under pressure into the central inlet passage 15 and from there outwardly into the two branch inlets 16 and thus into the inner ends of the valve cylinders 17. The hydraulic pressure projects the valve pistons 22 outwardly to open the by-pass passages 18 and permit fluid to flow under pressure from the master cylinder outwardly into said passages 18 and said openings 20 into the inner ends of the main cylinders 11. The fluid under pressure exerts force on the inner ends of the brake-actuating pistons 12 and moves said pistons 12 outwardly to forcibly project said brake shoes 25 and 26 against the brake drum 28.

When the by-pass passages 18 are opened the hydraulic pressure in the inner ends of said valve cylinders 17 will ultimately become equal to the hydraulic pressure in the inner ends of main cylinders 11. However, as the pressure on the brake pedal is being initially increased, the hydraulic pressure within the valve cylinders 17 will be greater than the hydraulic pressure in the main cylinders 11 and will maintain the valve piston in extreme projected position by maintaining a greater pressure against the inner ends of said valve pistons 22 than in the main cylinders 11. But as soon as the pressure on the brake pedal is stabilized and is no longer being increased, but merely held in brake-operating position, the hydraulic pressure within the main cylinders 11 and the valve cylinders 17 will be quickly equalized. Since the hydraulic pressure against the valve pistons 22 must be equal to the hydraulic pressure within cylinders 11 plus the force exerted by the springs 14, as soon as the hydraulic pressures in the cylinders 11 and 17 become equal, the springs 14 will operate to retract the valve pistons 22 and close off by-pass passages 18, trapping within the inner ends of main cylinders 11 all of the fluid which has flowed therein. The pistons 22 will continue to move inwardly until the hydraulic pressure against the inner ends thereof is equal to the sum total of the hydraulic pressure within the inner ends of main cylinders 11 plus the force exerted by the springs 14.

When the brake pedal is released the valve pistons 22 will move inwardly into extreme retracted position, where the recesses 17a will receive sealer flanges 23a and permit the central portions of the sealer caps 23 to firmly seat themselves against the central annular portions surrounded by the recesses 17a. It will be seen that the retraction of the valve pistons 22 after the release of the brake pedal will permit the brake-actuating pistons 12 to be retracted a proportionate distance and permit a predetermined normal clearance between the brake-shoes 25 and 26 and the brake drum 28. The brakes are now in perfect adjustment and will remain constantly in adjustment until the brake linings are completely worn out and have to be replaced. The volumes of fluid retained within the main cylinders 11 will remain constant until wear occurs on the brake-shoes 25 and 26, at which time the said volumes will be increased to maintain a predetermined clearance between brake-shoes 25 and 26 and brake drum 28, as will be described later.

The two principal factors which determine the clearance between the brake-shoes and the brake drum are the diameter of the valve pistons 22 with

relation to the diameter of the hydraulic pistons 12 and the distance which the valve pistons move after release of the brake pedal, or in other words, the volume of fluid which the outer ends of the valve pistons 22 displace within the inner ends of the main cylinders 11 during their operating stroke. These portions may of course be adjusted to maintain any desired predetermined adjustment of the brake-shoes 25 and 26 relative to the brake drum 28.

Often in the normal operation of the brakes the small pistons 22 will serve entirely to project the brake-shoes 25 and 26 against the brake drum 28 and will not move out a sufficient distance to open by-pass passages 18. This is true because the brake-shoes as now manufactured wear relatively slowly and it will not be necessary to increase the volume of fluid retained in the inner ends of main cylinders 11 until wear occurs on said brake-shoes. Due to the inherent slight compressibility of the brake-shoes and linkage between them and pistons 12 it is apparent that in cases of great emergency, when extreme sudden pressures are applied to the valve pistons 22, the said pistons 22 will be projected outwardly a sufficient distance to open the by-pass passages 18 and permit a slight amount of fluid to flow into the inner ends of the main cylinders 11, but normally the displacement of the outer ends of the valve pistons into the main cylinders 11 will be sufficient to operate the brakes until wear occurs on the brake-shoes 25 and 26.

As the brake-shoes 25 and 26 wear, the respective volumes of fluid retained within the inner ends of the main cylinders 11 must be increased to maintain the predetermined spaced relation between brake-shoes 25 and 26 and brake drum 28. Obviously, when the prior application of the brakes has produced wear on the brake-shoes 25 and 26, the valve pistons 22 will have to move outwardly a greater distance in order to apply the brakes, and in the event that there has been sufficient wear to permit said pistons 22 to open by-pass passages 18 a small amount of fluid will be permitted to enter the inner ends of cylinders 11, thus increasing the volume of fluid retained within said cylinders 11.

An alternative form of wheel cylinder embodying my invention designated by the letter B is illustrated in Figure 5. Wheel cylinder B operates substantially the same way in which cylinder A operates except that wheel cylinder B comprises only one-half of wheel cylinder A. Wheel cylinder B has only one piston which is adapted to operate on only one brake-shoe; therefore it is obvious that two type B wheel cylinders must be mounted on the backing plate 32, one at the top of said backing plate and the other at the bottom thereof. Of course each type B wheel cylinder will have its own inlet passage 33, but otherwise will operate substantially the same as previously described under type A. The purpose of having two type B wheel cylinders mounted within a brake assembly is to convert both brake-shoes into primary shoes. With the brake drum 34 rotating in the direction of the arrow shown in Figure 5 both shoes 35 will be primary shoes and the rotation of the drum will tend to "drag" the shoes into engagement with the drum.

It will be seen from the foregoing description that with my mechanism, regardless of the wear on the brakeshoes the actuating stroke in applying the brakes is always constant, as is the normal spaced relation between the shoes and the

drum. As the brake-shoes wear, the normal retracted position of the pistons 12 changes accordingly as the volume of fluid retained in the inner ends of the cylinders 11 increases to compensate for said brake-shoe wear. The resilient connection between the valve pistons 22 and said actuating pistons 12 permits the spaced relation therebetween to be varied both during operation and in the normal retracted position thereof. By providing brakes which are always maintained in constant adjustment it will be seen that the use of larger wheel cylinders is possible because the necessity of a safety reserve in the allowable foot-pedal travel to provide for wear on the wheel cylinders relative to the size of the master cylinder to increase mechanical advantage is eliminated by the fact that there is a definite limitation on the allowable foot-pedal travel and the fact that there must be some provision to permit wear on the shoes so that even if the brakes are not in perfect adjustment there will be sufficient "pedal" to apply the brakes. With my improved construction the wear on the shoes will be compensated for by my valve adjustment mechanism, which increases the normal residual volume of fluid retained in the cylinders 11 as wear occurs. Also the laborious manual adjustments which must be made from time to time on conventional hydraulically operated brakes is eliminated with my improved construction, saving not only labor costs but also material costs in manufacturing the manual adjustment mechanism. A very important safety factor is provided also by eliminating the chance for human error in neglecting to have the necessary manual adjustments made or in making poor adjustment in the conventional systems.

It will of course be understood that my invention or the working mechanism herein disclosed is by no means limited to brake-operating devices, but is equally applicable to other mechanisms when it is desired to maintain a constant predetermined actuating stroke and spaced relationship between a projectable element and a cooperating element related thereto.

It will, of course, be understood that various changes may be made in the form, details, arrangement and proportions of the parts without departing from the scope of my invention.

What I claim is:

1. A fluid operated system for projecting a normally retracted projectable element against an element adapted to cooperate therewith, comprising a fluid confining cylinder, an actuating piston working within said cylinder and adapted to be connected to a projectable element, means defining a passage for connecting said cylinder with a controlled source of fluid under pressure, a fluid displacing element projectable into said cylinder when subjected to fluid pressure from said source to displace a substantially predetermined volume of fluid in said cylinder, and a valve element operative in said passage to normally close the same but opening when more than said predetermined volume of fluid has been displaced, whereby a predetermined actuating stroke of said actuating piston and spaced relation between the projectable element in normal position and the element adapted to cooperate are maintained.

2. A fluid operated system for projecting a normally retracted projectable element against a cooperating element, comprising a fluid confining cylinder, an actuating piston working

within said cylinder and adapted to be connected to a projectable element, means defining a passage for connecting said cylinder with a controlled source of fluid under pressure, a fluid displacing element projectable into said cylinder when subjected to fluid pressure from said source to displace a substantially predetermined volume of fluid in said cylinder and project said projectable element a predetermined distance toward the element adapted to cooperate therewith, and a valve element connected with said fluid displacing element for movement therewith and operative in said passage to normally close the same but opening when more than said predetermined volume of fluid has been displaced by said displacing element to permit the volume of fluid in said cylinder to be increased to compensate for wear between said projectable element and said cooperating element, whereby a predetermined actuating stroke of said actuating piston and spaced relation between the projectable element in normal position and the element adapted to cooperate therewith are maintained.

3. A hydraulically operated system for projecting a normally retracted projectable element against a cooperating element, comprising a fluid confining cylinder, an actuating piston working within said cylinder and adapted to be connected to a projectable element, means defining a passage for connecting said cylinder with a controlled source of hydraulic fluid under pressure, a fluid displacing element projectable into said cylinder when subjected to fluid pressure from said source to displace a substantially predetermined volume of fluid in said cylinder and project said projectable element a predetermined distance toward the element adapted to cooperate therewith, a valve element connected with said fluid displacing element for movement therewith and operative in said passage to normally close the same but opening when more than said predetermined volume of fluid has been displaced by said displacing element to permit additional fluid under pressure from said source to flow into said cylinder, and a resilient member interposed between said fluid displacing element and said actuating piston to urge said displacing element inwardly and close off said valve to retain an increased volume of residual fluid within said cylinder to compensate for wear between said projectable element and the element adapted to cooperate therewith, whereby a predetermined actuating stroke of said piston and spaced relation between the projectable element in normal position and said cooperating element are maintained.

4. A hydraulically operated system for projecting a normally retracted projectable element against a cooperating element, comprising a fluid confining cylinder, an actuating piston working within said cylinder and adapted to be connected to a projectable element, means defining a passage for connecting said cylinder with a controlled source of hydraulic fluid under pressure, a piston valve working in said passage and responsive for operation to fluid supplied under pressure from said source and to have a portion thereof projectable into said cylinder to displace a predetermined volume of fluid therein, said valve normally closing said passage but opening the same when more than said predetermined volume of fluid has been displaced by said piston valve to permit additional fluid under pressure from said source to flow into said cylinder

and means for retracting said piston valve to close said passage whereby an increased volume of residual fluid is retained within said cylinder to compensate for the wearing off of the cooperating surfaces of said projectable element and the element adapted to cooperate therewith, whereby a predetermined actuating stroke of said piston and spaced relation between the projectable element in normal position and said cooperating element are maintained.

5. A hydraulically operated system for projecting a normally retracted projectable element against a cooperating element, comprising a fluid confining cylinder, an actuating piston working within said cylinder and adapted to be connected to a projectable element, means defining a passage for connecting said cylinder with a controlled source of hydraulic fluid under pressure, a piston valve working in said passage and responsive for operation to fluid supplied under pressure from said source and to have a portion thereof projectable into said cylinder to displace a predetermined volume of fluid therein, said valve normally closing said passage but opening the same when more than said predetermined volume of fluid has been displaced by said piston valve to permit additional fluid under pressure from said source to flow into said cylinder and a resilient member interposed between said piston valve and said actuating piston to urge said piston valve inwardly and close off said passage to increase the volume of residual fluid retained within said cylinder to compensate for the wearing off of the cooperative surfaces of said projectable element and element adapted to cooperate therewith, whereby a predetermined actuating stroke of said piston and spaced relation between the projectable element in normal position and said cooperating element are maintained.

6. A fluid operating mechanism comprising a cylinder, an actuating piston working in said cylinder, means defining a passage for connecting one end of said cylinder with a controlled source of fluid under pressure, means defining a valve chamber one end of which is interposed into said passage, said valve chamber having its other end portion communicating with said end of said cylinder, a piston valve working in said valve chamber to normally seal off said passage and being responsive for operation to fluid supplied under pressure from said source to have one end thereof projectable into said cylinder to displace a predetermined volume of fluid therein and having the other end adapted to open said passage when said predetermined volume of fluid has been displaced in said cylinder and permit additional fluid to be supplied to said cylinder under pressure from said source, and a resilient member interposed between said piston valve and said actuating piston to close off said passage and retain an increased volume of residual fluid within said cylinder.

7. A fluid operating mechanism comprising a wheel cylinder, an actuating piston working in said cylinder and adapted to be connected to a normally retracted projectable element of the type having means associated therewith for retracting the same, means defining a valve chamber having one end communicating with said end of said cylinder, means defining a passage for connecting the other end of said chamber with a controlled source of fluid under pressure, means affording lateral by-pass communication between an intermediate portion of said valve chamber

and said end of said cylinder, a piston valve working in said valve chamber in sealed relation thereto to normally seal off communication between said passage and said by-pass means and responsive for operation to fluid pressure from said source against one end of said piston valve to move said piston valve and normally project the outer end thereof a substantially predetermined distance into said cylinder to displace a substantially predetermined volume of fluid in said cylinder and project said element a predetermined distance, said piston valve permitting fluid under pressure from said source to flow into said cylinder through said by-pass means only after said piston valve has been moved more than said predetermined distance, and resilient means interposed between said actuating piston and said piston valve to close off said by-pass means and retain an increased volume of residual fluid within said cylinder, said

20

element retraction means supplying return pressure to aid said resilient member in seating said piston valve against said second mentioned end of said valve chamber.
